UNITED STATES PATENT OFFICE

2,452,873

AUTOMATIC BUILDER MOTION KNOCKOFF
FOR ROVING FRAMES

Johnnie J. Seawright, Goldville, S. C.

Application April 4, 1947, Serial No. 739,346

5 Claims. (Cl. 57—79)

1

This invention relates to a stop motion for Saco-Lowell roving frames such as model D, model J-3 and various other models having like parts. Many of the details of this mechanism are not shown in the present drawings, but are fully illustrated in a catalogue of parts of Saco-Lowell shops entitled model D Controlled draft Roving frames.

It is an object of this invention to provide means for stopping a roving frame and the like when the builder motion does not reverse itself due to the collection of lint and other foreign matter at certain parts of the mechanism and thus preventing breakage of various parts of the machine.

It is a well-known fact that when lint and other foreign matter collects in certain portions of the machine, that an intermittently rotating shaft which is urged by spring and cam means such as shown on plate F12-BD in said catalog fails to move. This shaft has a gear on one end thereof with a pair of segments extending approximately 160 degrees into engagement with a constantly rotating gear and thus the builder motion will not be arrested and reversed in its direction of travel and breakage of parts occur. By providing stop motion actuating means associated with the conventional mechanism of a roving frame of this type, this possibility is eliminated because in the operation of the builder motion, certain parts move up and down with the builder motion and in the case of failure of the builder motion to stop its downward or upward movement and reverse itself, certain mechanism is provided to be engaged by means associated with the builder motion to actuate the stop motion mechanism of the machine to stop the same.

It is therefore an object of this invention to provide means associated with a roving frame and the like for stopping the machine when the builder motion fails to operate properly, that is, by failing to stop its up or down movement and reverse itself.

Some of the objects of the invention having been stated, other objects will appear as the description proceeds when taken in connection with the accompanying drawings, in which

Figure 1 is a rear elevation of a portion of a Saco-Lowell model D or model J-3 roving frame and showing the invention applied thereto;

Figure 2 is an elevation of the central portion of Figure 1 and showing the same on an enlarged scale;

Figure 3 is an elevation partly in section and looking towards the left from the right-hand side

2

of Figure 2 or being taken along the line 3—3 in Figure 1;

Figure 4 is a sectional plan view taken along the line 4—4 in Figure 3;

Figure 5 is a schematic view, partly in section, and taken along the line 5—5 in Figure 2;

Figure 6 is a schematic view taken along the line 6—6 in Figure 3 and omitting certain parts;

Figure 7 is an elevation on an enlarged scale taken along the line 7—7 in Figure 2 with parts omitted.

Referring more specifically to the drawings, the numerals 10 and 11 indicate the third and fourth Samsons of a Saco-Lowell roving frame of several models among which are model J-3 and model D, which are joined together at their upper ends by means of a channel member 12. The lower ends of the Samsons are connected together by one or more shafts 15. The roving frame also has a spindle rail 13 and a bolster rail 14.

The spindle rail 13 has rotatably mounted therein a plurality of spindles 16 and these project upwardly through the bolster rail and the bolster rail has rotatably mounted thereon a plurality of bolsters 17 on which roving packages 18 are wound. The spindles support suitable fliers, not shown, on the top ends thereof which deposit the roving onto the bolsters 17. The spindle rail 13 and the bolster rail 14 both contain suitable conventional gearing, not shown, for imparting rotation to the spindles 16 and to the bolsters 17.

The roving frame is equipped with a pair of cone pulleys, the upper cone pulley being designated as 20 and is directly driven from the head of the machine by conventional mechanism as shown in said catalog and also as shown in a catalog entitled "Textile machinery, with special reference to the roving frames built by Saco-Lowell shops" and published in 1924. This gearing is conventional and is fully illustrated on pages 41 to 45, inclusive, of the last-named catalog. The cone pulley 20 has integral therewith a shaft 21 which is mounted in a bearing 22 in the Samson 10 and has a beveled gear 23 on the end thereof. The cone pulley 20 has a belt 25 thereon which is also mounted on a cone pulley 26 which usually has a pinion on the left-hand end thereof which meshes with a pinion 27 on a shaft 28 which extends into a gear box 29 where shaft 28

50 has fixed on the end thereof a beveled gear 30 which is adapted to mesh one at a time with beveled gears 31 and 32 which are integral with each other and being secured on a sleeve 33 fixed on a shaft 34 extending from the box 29. 55 The sleeve 33 is keyed for sliding movement on

the shaft 34 and has a peripheral groove 36 therein adapted to be engaged by a pin 37 (Figure 4) on one end of a lever 38 pivoted as at 40. This lever 38 has an arcuate slot 41 therein for cooperation with the other parts of the machine not necessary to describe for an understanding of this invention.

The pivot pin 40 rises upwardly from a housing 42 and the housing 42 rotatably mounts the lower end of a shaft 43 on the lower end of which is mounted a disc 44 (Figure 6), and immediately thereabove is an eccentric cam 45, all of which is shown in plate F12-BD in said roving frame catalog of parts. The lever 38 is hooked at its end nearest the observer in Figure 4, forming a cavity 46, in which the eccentric cam 45 has movement. The disc 44 which is disposed immediately below the cam 45 and fixedly secured on shaft 45 (Figure 6) has two pins 47 and 48 extending downwardly therefrom which are engaged by a lever 50 pivoted as at 51 and pressed against one of the pins 47 or 48 at a time by means of a tension spring 52 anchored to a spring perch 53 anchored on the Samson 10.

The arrangement just described, comprising the lever 50 urged by spring 52, tends to urge the shaft 43 to rotate in a clockwise manner looking down from the top of Figure 2 or looking down on Figure 6, the purpose of which will be later described. The shaft 43 has fixedly secured thereon a hub member 55 having arms 56 and 57 extending therefrom. The shaft is rotatably mounted in a L-shaped bracket 58 and immediately above the horizontal portion of the L-shaped bracket 58 there is fixed on shaft 43 a worm 60. The shaft 43 projects upwardly through a bearing 61 and on its upper end has fixedly mounted thereon a beveled gear 62 which beveled gear is segmental in that it has disposed 180 degrees apart from each other blank spaces of about 15 degrees each designated by reference character 63 (Figure 3). Thus it is seen that the spring 52 tends to urge the shaft 43 to rotation to cause one of the toothed portions of beveled gear 62 to engage the beveled gear 23 when permitted to do so by movement of one of the arms 56 and 57 past a vertical reciprocating mechanism, to be presently described.

The bracket 38 has disposed therein a stub shaft 65 on which is rotatably mounted a worm gear 66 having a hub portion to which the reference character is applied in Figure 3, which meshes with worm 60. There is also rotatably mounted on the stub shaft 65 a pinion 67 disposed in spaced relation to the worm gear 66 and between the worm gear 66 and pinion 67 is disposed a clutch mechanism 68 which at times is adapted to declutch the worm gear 66 from the pinion 67. This happens when the stop motion mechanism is operated as will be presently described.

The pinion 67 meshes with a tension compound gear 70 rotatably mounted on a stud bolt 71 and also integrally driven, but separable from the pinion 70, is a change gear pinion 72 which meshes with the lower toothed portion of the conventional rack 73 of the roving frame. The clutch 68 has extending therefrom an arm 74 which is slotted as at 75, in which slot there is disposed for movement a pin 76, fixed on the lower end of a stop motion lever 77 which is pivoted as at 78 on the bar 12 and projects upwardly and is secured as at 80 to a shipper shaft 81 which is connected to the conventional belt shifting or other stop motion mechanism of the roving frame.

Pivoted to the lever 77 as at 82 is one end of a lever 83 which is notched to provide a shoulder 84 and which lever 83 projects through a suitable opening 85 in the Samson 10 and the shoulder 84 is adapted to engage the left side of a plate 86 secured to the Samson 10 to prevent its normally moving to the right in Figure 2.

The lever 77 is normally urged in a counter clockwise direction by means of a tension spring 87 secured at one end near the lower end of the lever 77 and at its other end to an adjustable spring perch 88 secured to a bracket 89 mounted on Samson 11. When the lever 77 has been moved to the position shown in Figure 2 to stop the machine, this actuates the conventional clutch 68 and declutches the worm gear from the pinion 67 and thus allows the rack 73 to be manually restored to starting position.

Secured on the Samson 10 is a bracket 90 in which is rotatably mounted a vertically disposed stub shaft 91 having a pinion 92 fixed thereon which meshes with the side teeth 93 in the rack bar 73. On the upper end of shaft 91 is fixed a pinion 94 which meshes with a pinion 95 forming a part of a tube gear which has integral therewith a tubular portion 96 which has on its upper end a pinion 97. The pinion 97 meshes with a pinion 100. The pinion 100 is mounted on the lower end of a shaft 101 which is rotatably mounted in a bearing 102 integral with a bracket 103 secured on one side of the Samson 10. The shaft 101 projects upwardly and has a hand wheel 104 fixed on its upper end which can be turned for resetting the rack 73 and associated parts to initial position.

The pinion 100 meshes with the pinion 97, previously described, on the upper end of sleeve 96. The sleeve 96 as well as the pinions 95 and 97 have a squared hole passing longitudinally thereof in which is slidably mounted a squared shaft 105. One side of the Samson 10 has a vertically extending rib 106 on which is slidably mounted a vertically extending block 107. This block 107 has extending forwardly therefrom an arm 108 which is secured by any suitable means, such as a screw 109, to the lower surface of the bolster rail 14 so that up and down movement of the bolster rail will likewise move the block 107 up and down.

The block 107 has a pair of stub shafts 110 and 111 projecting rearwardly therefrom, the other ends of which support a plate 112. The plate 112 has spaced bearings 113 and 114 in which the shaft 105 is rotatably mounted. The shaft 105 has two oppositely threaded portions 115 and 116 thereon.

Threadably mounted on threaded portion 115 is a bracket 117 which has vertically disposed portions 118 and 119 integral therewith. The plate 112 has an outwardly projecting portion 120 which prevents rotation of member 117 as well as a member 121 threadably mounted on the lower threaded portion 116 of shaft 105.

The member 121 has integral therewith an upwardly projecting portion 122 which is likewise adapted to engage the portion 120 of plate 112 to prevent rotation of the member 121. The member 121 has a vertically disposed and downwardly projecting portion 123.

The above described parts are conventional parts in a Saco-Lowell roving frame of several types such as the D type or the J-3 type and the like. It is with this mechanism that this stop-motion mechanism is adapted to cooperate.

The downturned leg of lever 83 is designated

by reference character 83'. This has a pin 130 fixed therein on which is slidably mounted the upper ends of links 131 and 132, said links having elongated slots 133 and 134 respectively therein. These links 131 have turn buckle adjusting means 135 and 136 therein and the lower ends of the links are pivoted as at 137 and 138 to an angle bar 140. This angle bar has welded to the lower surface thereof a flattened portion of a pinion 141. This pinion is rotatably mounted on a stub shaft 142 extending laterally from an arm 144 extending upwardly and outwardly from a bearing 145 secured to the Samson 10 by any suitable means such as bolts 146. Rotatably mounted in the bearing 145 is a stub shaft 147 which is confined against endwise movement by collars 148 and 149. On the outer end of shaft 147 is fixedly secured a quadrant 150 whose teeth are adapted to be engaged by the pinion 141 fixed on the lower surface of angle bar 140. Secured to the right-hand side lower portion of quadrant 150 by means of bolts 152 is a dog 153 which has an arm 154 passing out adjacent the periphery of the quadrant 150.

The portions 119 and 123 of the brackets 117 and 121 have vertically disposed grooves 155 therein, each having a plurality of tapped holes 156 into which a set screw 157 is adapted to be secured and which said screw penetrates a slot 158 in angle-shaped tongues 160 and 161 which are adapted to engage the arm 154 when the builder motion does not operate properly to stop the machine.

Method of operation

The parts are shown in Figure 1 in operative condition while the machine is properly running, and in Figure 2, the parts are shown in the position they will occupy when the machine has been stopped due to the fact that the builder motion has moved upwardly too far. The same position of parts as appears in Figure 2 would also occur when the builder motion moves down too far to cause the lip 160 to engage the tongue 154, except that angle bar 140 would be swung in a counterclockwise direction.

During the normal operation of the machine, the up-and-down movement of the bolster rail will cause the block 107 to move upwardly and downwardly, and the shafts 110 and 111 will cause the plate 112 likewise to move upwardly and downwardly during a building operation. This will cause the brackets 117 and 121 along with the shaft 105 to move upwardly and downwardly since the upper end of shaft 105 has sliding movement in the sleeve 96. This movement will cause the tongue 161 not to rise far enough to engage the arm 154 and likewise upon downward movement, the projection 160 will not engage arm 154 to move the quadrant 150.

As has before been described, the spring 52 is pushing against one of the pins 47 or 48 and is tending to rotate the beveled segmental gear 62 to where it will engage the constantly driven beveled gear 23. The brackets 117 and 121 will move down just far enough to let arm 56 pass, and likewise will move just far enough upwardly to let arm 57 pass during the normal operation of the builder motion, for as the brackets 117 and 121 move up and down, arms 56 and 57 will alternately be sliding along the ribs 122 and 118, respectively. As the builder motion reaches its lowermost position, the arm 57 will pass by the upper end of surface 118 and allow the spring 52 to urge the shaft far enough to where one of

the segments on segmental gear 62 will engage constantly rotating beveled gear 23 and impart a half revolution to the shaft 43. As the builder motion moves upwardly, the arm 56 will be sliding along portion 122 and when it reaches its uppermost point ready for a reversal of the builder motion, the spring 52 will cause the arm 56 to pass below the lower end of portion 122 to engage the other portion of the segmental gear 62 with the beveled gear 23 to impart another half revolution to shaft 43.

Now, in case of the uppermost position or the lowermost position of the brackets 117 and 121 being reached, and should there be lint and other foreign matter in the pinions 67, 70 and associated parts so that the tension in the spring 52 will not be sufficient to initiate rotation of the shaft 43 to reverse the builder mechanism, it is seen that the builder mechanism would continue upwardly or downwardly and break various portions of the machinery unless it is stopped immediately. If the builder motion moves upwardly too high, the tongue 161 will engage the portion 154 and move the parts to the position shown in Figure 2 and should the builder motion move downwardly too far, the spring 52 not being able to initiate rotation of shaft 43, then the tongue 161 would engage portion 154 and rotate the segment 150 in the opposite direction or in a clockwise direction in Figure 2, and this would swing the angle bar 140 in a counter-clockwise manner in Figure 2 to cause link 132 to be raised upwardly to engage pin 130 to move the portion 83' to the position shown in Figure 2.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a roving frame having a bolster rail which is moved up and down by a conventional builder motion, said frame having a member carried by the bolster rail and having a rotatable shaft carried thereby and said shaft having oppositely threaded portions thereon and a pair of brackets mounted on the threaded portions, said frame having driven means for imparting rotation to the shaft to move the two brackets incrementally towards each other during the placing of roving on the conventional bobbins of the machine, said frame having a second rotatable shaft provided with a pair of arms disposed 180° apart and due to the rotation of the second shaft being adapted to pass below and above said brackets during their normal up and down movement, said frame also having a stop motion lever and means connected thereto for holding the stop motion lever in running position, an outwardly projecting tongue adjustably mounted on each of the brackets, an oscillatable member having a connection with the member for holding the stop motion lever in running position and also having a portion projecting into the path of the tongues mounted on the two brackets, whereby when the brackets move below or above a predetermined point, one of the tongues adjustably mounted thereon will engage the portion projecting into the paths of the tongue mounted on the brackets to move the stop motion lever to a position to stop the frame.

2. In a roving frame having a builder motion

and a member carried by the builder motion for up-and-down movement therewith, said frame also having a stop motion lever biased to move to a position to stop the frame and having means for holding the lever against movement to stop the machine, the member carried by the builder motion having a pair of brackets movable incrementally towards each other during operation of the frame, said frame also having a rotatable shaft provided with two arms at different levels which are adapted to pass below and above the brackets during operation of the frame, each of said brackets having adjustably secured thereon an outwardly projecting tongue, an oscillatable member mounted on the frame and having a pair of links connected thereto at one end and having their other ends slidably connected to the means for holding the stop motion lever against movement towards stopping position, said oscillatable member having an arm projecting into the path of the tongues so that when the brackets move beyond their normal stopping point one of the tongues will engage the arm on said oscillatable member and thus move the means for holding the stop motion lever to released position.

3. In a roving frame having a builder motion and a stop motion lever biased to move to stopping position and having means for restraining the stop motion lever from moving to stopping position, an oscillatable member carried by the frame, a pair of spaced projections carried by the builder motion, the oscillatable member having an arm projecting therefrom into the path of the projections when the builder motion moves beyond its normal path of travel, a pair of links connected to the oscillatable member and connected to the means for restraining the stop motion lever against movement, whereby when the builder motion moves beyond its normal limits, one of the projections will engage the arm on the oscillatable member to move the restraining means to released position.

4. In a roving frame having a builder motion and stop motion means biased to move to stopping position and having means for restraining the stop motion means against movement, a pair of spaced projections moved in an up and down path within certain limits by the builder motion, means disposed within the same plane traveled by the projections but beyond their normal path and adapted to be engaged by one of the projections when the builder motion moves beyond its normal path, and a connection between the last-named means and the restraining means for moving the restraining means to release the same when one of the projections engages the last-named means due to the builder motion travelling beyond its normal path.
5. In a roving frame having a builder motion and stop motion mechanism and a pair of spaced brackets carried by the builder motion for up-and-down movements within a defined path, each of said brackets having a tongue projecting therefrom, an oscillatable member carried by the frame and having an arm projecting into the path traveled by the brackets but being disposed beyond the normal path of travel of the tongues, and means movable by the oscillatable member when its arm is engaged by one of the tongues on account of the brackets traveling beyond their normal path, for moving the stop motion mechanism to stop the frame.

JOHNNIE J. SEAWRIGHT.
